(57) **CLAIM**

The ornamental design for a snow skate, as shown and described.

DESCRIPTION

FIG. 1 is a perspective view of the snow skate of the present design;

FIG. 2 is a top view of the snow skate of FIG. 1;

FIG. 3 is a bottom view of the snow skate of FIG. 1;

FIG. 4 is a right side view of the snow skate of FIG. 1, the left side view being identical thereto;

FIG. 5 is a front view of the snow skate of FIG. 1, the rear view being identical thereto; and,

FIG. 6 is an enlarged cross-sectional view of the snow skate of FIG. 1, as taken along line 6—6 in FIG. 1, in a direction indicated by arrows.
